(57) **CLAIM**

The ornamental design for a radioactive soap, as shown and described.

DESCRIPTION

FIG. 1 is a front perspective view of the radioactive soap of the present invention showing our new design;

FIG. 2 is a front elevational view thereof;

FIG. 3 is a top plan view thereof; and

FIG. 4 is a bottom plan view thereof.

FIG. 5 is a left side elevational view thereof;

FIG. 6 is the right side elevational view thereof; and,

FIG. 7 is a rear elevational view thereof.
